UNITED STATES PATENT OFFICE.

CHARLES D. GOLDEN, OF CHICAGO, ILLINOIS.

DESIGN FOR A CIGAR-LIGHTER, &c.

SPECIFICATION forming part of Design No. 26,634, dated February 16, 1897.

Application filed December 18, 1896. Serial No. 616,196. Term of patent 3 $\frac{1}{2}$ years.

To all whom it may concern:

Be it known that I, CHARLES D. GOLDEN, a citizen of the United States, residing at Chicago, in the county of Cook and State of Illinois, have invented and produced a new and original Design for a Cigar Lighter and Cutter, of which the following is a specification, reference being had to the accompanying drawing, showing the same, in which the figure is a front elevation of a cigar cutter and lighter embodying the features of my design.

The leading features of my design consist in the spirally-arranged diamond-shaped spaces forming the lower half and the spirally-arranged ornamentation in relief forming the upper half of the vase-shaped lighter, and in the radially-grooved and foliated base, the circular beaded ornamentation and foliation of the body of the cutter, together with the configuration of said body.

In the drawing, *a* represents the base proper of the entire structure, which consists of a flat body having a peripheral ogee molding. Near the respective ends of the part *a* are lighters, each consisting of a pear-shaped body *b*, ornamented with diamond-shaped spaces in low relief arranged spirally to the axis of the body. Ornamental bands *c d*, at or near the middle, separate the main body from the upper portion *e*, which consists of spirally-arranged molding. The whole is sur-

mounted by an ornamental top *f*, forming the thumb-piece of the lighter.

Centrally located on the base *a* is the cutter *g*, which consists of a vase-like structure 35 surmounted by a lamp. The base of the cutter is rounded and ornamented with radial grooves *h*, while the intermediate space between the base and body is surrounded by a central band *i*, protruding from which above 40 and below are foliations *j*. The lower part of the main body is embellished with foliated ornamentation *k*.

The central space of the body is utilized to receive a circular clock-face *l*, which is surrounded by a beaded ornamentation *m*, above 45 which and branching from a central flower *n* are leafed branches, while ornamental handles are formed upon the sides. The lamp or burner above is provided with a flaring 50 shade scalloped at the top and ornamented in relief with a series of dots.

I claim—

The design for a cigar lighter and cutter, substantially as shown and described.

In testimony whereof I have signed this specification, in the presence of two subscribing witnesses, this 7th day of December, 1896.

CHARLES D. GOLDEN.
